UNITED STATES PATENT OFFICE.

WILLIAM H. GILLESPIE, OF BIRMINGHAM, ALABAMA.

SYRUP-MEASURING FAUCET.

1,053,169.

Specification of Letters Patent. Patented Feb. 18, 1913.

Application filed March 22, 1912. Serial No. 685,567.

To all whom it may concern:

Be it known that I, WILLIAM H. GILLESPIE, a citizen of the United States of America, residing at Birmingham, in the county 5 of Jefferson and State of Alabama, have invented certain new and useful Improvements in Syrup-Measuring Faucets, of which the following is a specification.

My invention relates to an improved device 10 for measuring fluids and particularly for measuring the necessary quantity of syrups for mixing soda fountain drinks.

My object is to provide a measuring valve which has a means to vary its capacity so 15 that it will, for each operation, measure any desired quantity of the syrup, such means being preferably adjustable from without the casing in which the valve is seated.

My invention further comprises the features 20 of construction and arrangement of parts, all of which are hereinafter more particularly described and claimed, reference being had to the accompanying drawings, in which:—

25 Figure 1 is a side elevation of my invention attached to a receptacle for holding syrup. Fig. 2 is a vertical longitudinal section through Fig. 1, with the valve inverted. Fig. 3 is a vertical transverse cross sectional view taken through the center of the inverted valve and its casing.

Similar reference numerals refer to similar parts throughout the drawings.

I provide any suitable form of receptacle 30 or retainer for the fluid to be measured, preferably a glass jar or vessel 1 having a removable cover 2 and having its bottom edge externally threaded at 3 to receive a threaded ring 4 which engages the bottom 35 face of an annular flange 5 on the valve casing 6. A packing ring 7 is interposed between the bottom of the jar 1 and the flange 5 so that when the ring 4 is screwed up tight a close joint is made. The valve casing 6 is provided with a central port 8 which 40 opens into the top of a horizontal cylindrical valve chamber 9 in which is seated a hollow cylindrical valve 10. An outlet port 11 in the bottom of said valve seat 9 communicates with a discharge pipe 12. A screw 45 threaded plug 13 is threaded into the open end of the valve chamber 9 and is provided with a central opening through which projects a stem 14 which is made integral with 50 or suitably fastened to a plunger 15 which is provided with peripheral threads which

mesh with internal threads at the end of the valve left open for the insertion of the plug 15. The chamber in the valve is preferably cylindrical. The valve is provided with a single port 16 which opens into the chamber therein and is in alignment with the ports 8 and 11, so as to register with one or the other, according to the position of the valve. The valve has a stem 17 projecting through an opening in the integral end wall of the valve casing and is provided with a handle 18 for turning the valve. The closed end of the valve is provided with an annular ridge 19 which bears against the adjacent end wall of the casing and serves to reduce the friction at that point. The valve stem also has attached to it a stop pin 20 adapted to engage stop shoulders 21 and 22 which are attached to or cast integral with the end wall of the valve casing. The stem 14 is adapted to be engaged by a suitable implement and turned to adjust the plunger 15 in the valve to regulate the capacity of the chamber in the valve so that it will measure the desired quantity of syrup.

In operation, the valve normally stands in the position shown in Fig. 1, with its port 16 registering with the port 8. In this position the valve effectively closes the port 11 as it makes a fluid tight fit in its valve seat. The chamber in the valve fills with syrup and when it is desired to discharge its contents, the valve stem 18 is swung to its lowered position, the pin 20 engaging stop 21 and arresting the valve with its port 16 registering with the port 11 when the valve will discharge its measured contents through the discharge pipe 12 into a glass. It will be noted that the ports 11 and 16 are made larger than the port 8 to expedite the discharge of the valve's contents. The screw plug 13 engages the open end of the cylindrical valve and holds it against longitudinal movement in its seat.

100 The details of construction may be varied within the scope of my invention and I therefore do not desire to limit myself specifically thereto.

Having thus described my invention, what I claim as new and desire to secure by Letters Patent, is:—

1. The combination with a casing having side openings and provided at its ends with fluid tight heads, one of which is removable and both of which have contracted openings, of a measuring valve receptacle adapted to

be inserted within the casing and being open at the side to coöperate with the casing side openings, said receptacle being open at one end which is internally threaded, an adjustable plug which is threaded into the open end of said receptacle and has a reduced stem which projects through the opening in one head of the casing, and an operating member for the receptacle which projects 10 through the opening in the other head of the casing, substantially as described.

2. The combination with a casing open at one end and provided at the opposite end with a head in which is an opening, there being inlet 15 and outlet openings in the sides of the casing, of a measuring valve receptacle within the casing and open at the side and at same end as the casing, a spindle carried by the receptacle and projecting through the opening in 20 the head, an operating member on said spindle, a detachable closure for the open end of the casing and having a contracted opening, an adjustable member movable in the open end of the receptacle to vary its volumetric 25 capacity, a round stem of relatively small diameter which is connected to said member and projects through the contracted opening in said closure, substantially as described.

3. The combination with a casing having 30 side openings and end openings, one end opening being contracted and the inner wall of the casing being threaded at the other end, of a measuring valve receptacle within the casing and having a side opening adapted 35 to register with one or the other of said casing side openings and an end opening at the threaded end of the casing, an operating device for the receptacle which projects through said contracted opening, an ap- 40 pertured closure adapted to be screwed into the threaded end of the casing and engage the open end of the receptacle, and an adjustable plug which closes the open end of the receptacle and has a stem which projects 45 through the aperture in said closure.

4. In a measuring faucet, the combination with a casing having openings in its sides

and at one end and being provided at the opposite end with a head in which is a contracted opening, of a measuring receptacle 50 rotatably mounted within said casing and having an opening adapted to register with either side opening in the casing, an operating member for the receptacle which extends with a fluid tight fit through the contracted 55 opening in the casing head, said receptacle having an interiorly threaded end which is open at the same end as the casing, a screw plug which is threaded into the open end of the receptacle and has a reduced round op- 60 erating stem, and a detachable screw cap which closes the open end of the casing and has a contracted opening through which said stem projects with a fluid tight fit, said stem having a tool engaging portion at its 65 outer end.

5. The combination with a casing having side openings and provided at its end with fluid tight heads, one of which is screwed into an end of the casing and both of which 70 heads have contracted openings, of a measuring valve receptacle adapted to be inserted through the open threaded end into the casing and being itself open at the side to coöperate with the casing side openings and 75 at its end adjacent to the threaded end of the casing, an adjustable plug which is screwed into the open end of said receptacle and has a reduced stem which projects through the opening in one head of the cas- 80 ing, and an operating member for the receptacle which projects through the opening in the other head of the casing, said receptacle having an annular bearing flange at one end and at its other end being adapted 85 to engage the head which is screwed into the casing to be held in position thereby, sub- stantially as described.

In testimony whercof I affix my signature in presence of two witnesses.

WILLIAM H. GILLESPIE.
